UNITED STATES PATENT OFFICE.

JAMES H. RAND, JR., OF TONAWANDA, NEW YORK.

CARD-INDEX SYSTEM.

1,397,982.

Specification of Letters Patent. Patented Nov. 22, 1921.

Application filed May 21, 1917. Serial No. 169,883.

To all whom it may concern:

Be it known that I, JAMES H. RAND, Jr., a citizen of the United States, residing at Tonawanda, in the county of Erie and State 5 of New York, have invented a new and useful Improvement in Card-Index Systems, of which the following is a specification.

This invention relates to card index systems of the overlapping card type, in which 10 a series of cards or card holders are so disposed in overlapping and spaced relation to each other that marginal portions of the cards or card holders bearing index matter, or index members are exposed and visible 15 one above another. More particularly the invention relates to card index systems of this type in which the cards or card holders are provided with tongues or parts whereby the cards or card holders interlock or nest 20 together in such a manner that one card or card holder is supported by another and one card or card holder cannot be removed from the series without first moving it out 25 of interlocking engagement with an adjacent card or card holder.

In this specification the term "card," except where otherwise apparent, is used in a broad sense to denote either a piece of cardboard, paper or other member analogous to 30 a card having information printed or written directly thereon, or a member analogous to a card on which a separate card, slip of paper or the like, bearing the information is suitably retained so that this member or 35 card holder with its attached separate information slip can be manipulated and used like a card.

One object of this invention is to produce a practical and desirable card index system 40 of this nature in which the index members or exposed portions of the cards that bear the index matter are covered and protected by transparent sheaths or protectors which coöperate to interlock the cards and retain 45 them in the overlapped spaced relationship. Other objects of the invention will appear from the following description and claims.

In the accompanying drawings:—

Figure 1 is a front elevation on a reduced 50 scale of a series of overlapping cards embodying the invention; showing the same in position on the frame or support for the same.

Fig. 2 is a front elevation, full size, of one 55 of the cards and its sheath, a portion of the

supporting frame being shown partly in elevation and partly in section.

Fig. 3 is a front elevation, on a reduced scale, of one of the cards removed from the frame and sheath and before the same is 60 folded to form the index portion.

Fig. 4 is a fragmentary perspective view of one of the complete cards.

Fig. 5 is a sectional perspective of one of the card sheaths or protectors. 65

Fig. 6 is a fragmentary section of one of the cards with the sheath or protector in place thereon.

Fig. 7 is a cross section of a plurality of the cards, showing the same interlocked but 70 removed from the frame.

Fig. 8 is a fragmentary front elevation, similar to Fig. 1, showing a portion of the series of cards raised in the frame to expose the information appearing on one of the 75 cards.

Fig. 9 is a fragmentary cross-section of the frame and the cards thereon.

Fig. 10 is a front elevation, on a reduced scale, of a modification of the invention, 80 showing a card holder with a separate information card or slip retained thereon, the card being partially withdrawn from the holder and the index slip being partially drawn from the sheath. 85

Fig. 11 is a section, full size, on line 11—11, Fig. 10.

Fig. 12 is a front elevation, on a reduced scale, of another modification of the invention. 90

Fig. 13 is a section on line 13—13, Fig. 12.

Fig. 14 is a front elevation, partly in section, showing another modification.

Fig. 15 is a sectional perspective view of the cards shown in Fig. 14. 95

Figs. 16 and 17 are sectional perspectives of still other modifications.

Referring first to the construction shown in Figs. 1-9; A represents one of the cards which are arranged in overlapping relation 100 as shown in Fig. 1, in a suitable frame or support B, which is provided at its opposite side edges with the usual inturned flanges b forming guides b' for retaining the cards on the frame. The cards A can be made of 105 thin cardboard, paper or other suitable sheet material. Preferably they are made of comparatively thin flexible paper, as thereby the cost of the cards is reduced and the superposed portions of the cards occupy much 110

less space in the guides of the frame and permit the cards to slide much more freely in the guides than if thicker cards were used. C represents a sheath or protector which is applied to the upper marginal portion of each of the cards A. This sheath is preferably composed, as shown, of a front strip of thin, transparent celluloid 15 and a back or tongue strip 16 of thin cardboard or relatively stiff paper secured to the celluloid strip 15 below the upper edge thereof by staples or other suitable fastening devices 17. The lower portion 18 of the celluloid strip is bent rearwardly and upwardly between the body portion of the front strip and the back strip, thus forming an open ended pocket. In the construction shown in Figs. 1-9, the upper marginal portion of the card A, see Fig. 4, is folded first downwardly as indicated at 19 and then upwardly, forming a front index member or portion 20 on which is written or printed the name of the person represented by the card or other matter indicating the nature of the information contained on the card. By folding the card in this way the index matter can be printed on the front face of the card, that is on the same face thereof on which the information on the body of the card is printed. The folded portion of the card is slipped endwise into the pocket of the sheath C so that the sheath is retained on the card and the index member 20 is protected by the sheath while the matter thereon can be read through the transparent front wall of the sheath. The card depends from the sheath between the back strip 16 and the upwardly bent portion of the celluloid front strip, as clearly shown in Fig. 6. The back strip of the sheath shown is preferably provided with slits 21, see Fig. 5, below and parallel with the staples 17. The upper folded edge of the card is adapted to engage the edges of these slits, which act as stops to prevent the cards from wedging in between the front and back strips of the sheath and thus making it more difficult to slip the card into and out of the sheath. The stop slits could be provided in the front strip if desired, but they are preferably made in the back strip, as stated.

Preferably, the folded portion of the card forming the index member is shorter than the body portion of the card, and the sheath is made of approximately equal length so that when the cards with the sheaths thereon are arranged in the supporting frame B the opposite end portions of the cards will extend into the guides formed by the flanges b of the frame while the index portions 20 and the sheaths will project forwardly from the cards between the frame flanges and will not extend into the guides of the frame. The cards are nested or interlocked one with another and retained in spaced relationship,

as shown in Fig. 1, by inserting the upper portion of the sheath for one card up between the pocket and the back strip of the sheath for the next card above and in front of the body of the latter card, as shown in Fig. 7. As thus arranged the body portions of the cards are disposed one behind another and the lower front portion of each sheath and the index member 20 of the card therein are exposed to view beneath the sheath and the index portion of the next card above. A card or group of cards thus assembled can be readily inserted into place in the frame by bowing or springing the card or group of cards so as to insert the opposite ends of the card or group into the opposite guides b' of the frame. The cards are retained in the frame by the end portions thereof which extend beyond the ends of the sheaths into the guides. As the cards overlap for the greater portion of their height, the end portions of each card extend back of the corresponding portions of a number of other cards and the requisite stiffness or strength is thus provided to hold the cards securely in the frame, although the cards may be made of thin, flexible pieces of paper. Since the cards are thin, the end portions thereof do not bind or stick in the guides notwithstanding that there are a number of thicknesses in all portions of the guides, and the cards can slide or slip up and down in the guides freely without requiring deep guides. When it is desired to examine a card the sheath for this card is grasped and raised vertically in the frame, which lifts the sheaths above the same together with their cards until the face of the desired card is exposed to view, as shown in Fig. 8. When the card is released, it, together with the cards above it will slide down by gravity into place in the frame behind the next lower card with the sheath of the card which has been examined overlapping and interlocking with the sheath for the next card below. The cards slide very freely in the frame and can thus be manipulated and examined readily. Any desired card can be readily removed from the frame by similarly raising the card and then disengaging its sheath from the next sheath above and removing the card and sheath from the frame. In a similar manner a card can be readily inserted at any desired point between any two cards in the series.

If it is desired to hide from view the body of the lowermost card of the series in the frame, this can be conveniently done by means of a cover or plain card 22 which is inserted in the frame in front of the face of the lowermost card, as shown in Fig. 1.

In the construction shown in Figs. 10 and 11, instead of a card having information printed or written thereon as before explained, a plain card or card holder A' is

connected to the sheath C' and a card or slip 23 on which information is written or printed is removably secured or retained in place on this card holder A'. As shown, the 5 card holder A' has a single, downwardly folded, upper marginal portion 24, which is slipped into the pocket of the sheath C' for retaining the card holder in the sheath and the information card or slip 23 is inserted 10 endwise into the card holder A' between the downwardly folded portion 24 and an upwardly folded, lower marginal portion 25 of the card holder A'. In this form of the invention a separate narrow index slip 26 is 15 inserted into the pocket of the sheath in front of the downwardly folded marginal portion 24 of the card holder, this slip bearing the name or other matter indicative of the information contained on the card 23. 20 By the use of this construction it is possible to provide the holders and sheaths for index cards already in use and it is only necessary to slip the index card having the information thereon into the card holder A' and 25 without puncturing, forming or in anywise altering the card to enable its attachment to the card holder. The upper marginal portion of the index card which has the index name or matter thereon is hidden behind the 30 folded upper portion 24 of the card holder, hence the reason for the separate index slip 26. These index slips are preferably furnished in sheets scored or weakened on parallel lines adapting the slips to be readily 35 separated from the sheets. The index matter can thus be readily typewritten or printed on the sheet of the index slips and the slips then separated for insertion into the sheaths.

Figs. 12 and 13 show another construction 40 for employment with cards already in use. In this construction the sheath C² is made with a wider back strip 28 which depends farther below the pocket of the sheath than the back strip shown in the other constructions and this back strip is provided with slits 29 near its ends into which lugs 30 on a card 31 are adapted to engage for retaining the card on the back strip. Any other suitable means for securing the card to its back 45 could be employed. In this construction a separate index slip 32 similar to that shown in Figs. 10 and 11 is employed. The cards and sheaths shown in this construction are assembled as in the other constructions by 50 inserting the upper edge of the sheath for one card up between the pocket and the back strip of the sheath for the next card above.

In the several constructions above described the sheaths form in effect tongues on the cards whereby the cards are interlocked in overlapped relation, and in addition to this function the sheaths cover and protect the index members. For some card systems it is desirable to employ cards with tongues 55 which cooperate in a similar manner to inter-

lock the cards and provide exposed index portions, but in which the protecting covers or sheaths are omitted. Figs. 14 to 17 show such constructions. In the form shown in Figs. 14 and 15 the cards A² are folded the 70 same as the cards in the first construction described, except that the index portion or fold 33 extends above the upper edge of the body portion of the card. In assembling these cards the folded part or tongue of one 75 card is inserted between the folded tongue and body part of the next card, as shown in Fig. 15. A portion of each tongue is exposed below the next tongue and the index matter is written or printed on these exposed 80 parts.

Fig. 16 shows a form in which the tongue 84 is formed by a single folded margin of the card A⁴ stapled between its edges to the body of the card, and Fig. 17 shows another 85 form in which the tongue 35 is formed by a separate strip of material secured, as by staples, between its edges to the body of the card A⁵. In the constructions shown in Figs. 14 to 17, as in the other constructions, 90 the ends of the card project beyond the ends of the tongue and enter the guides of the frame for holding the cards thereon, and the tongues project forwardly between the 95 guide flanges of the frame.

I claim as my invention:

1. In a card system, a series of cards, a sheath connected to each card adjacent to one margin thereof for protecting an index member for the card, said cards being assembled with the sheath of each card nested between the sheath and the body of the next card in the series, whereby said cards are interlocked and spaced with their sheaths projecting one beyond another. 100

2. In a card system, a series of cards, a sheath connected to each card adjacent to one margin thereof and extending toward the opposite margin of the card in front of the card for protecting an index member 110 for the card, said cards being assembled with the sheath of each card nested between the sheath and the body of the next card in the series, whereby said cards are interlocked and spaced with their sheaths projecting one beyond another. 115

3. In a card system, a series of cards, a sheath connected to each card adjacent to one margin thereof for protecting an index member for the card, said cards being assembled with the sheath of each card inserted and interlocked between the sheath and the body of the next card in the series, and each card and its sheath having means for limiting the insertion of the sheath of the next 125 card between the same, whereby said cards are spaced with their sheaths projecting one beyond another.

4. In a card system, a series of cards, a sheath connected to each card adjacent to 130

- one margin thereof for protecting an index member for the card, said sheath extending above and below its point of connection with the card, and said cards being assembled with the sheath of each card nested between the sheath and the body of the next card in the series, whereby said cards are interlocked and spaced with their sheaths projecting one beyond another.
10. 5. In a card system, a series of cards, a sheath connected to each card adjacent to one margin thereof and provided with a pocket which contains and protects an index member for the card and with a thin edge portion which projects beyond the card and is adapted to nest between the sheath and the body of the next card in the series, whereby said cards are interlocked and spaced with their sheaths projecting one beyond another.
15. 6. In a card system, a series of cards, a sheath engaged with one margin of each card and comprising a pocket for an index member located in front of the card and a tongue which extends back of the card, said cards being assembled with the sheath of one card nested between the sheath and the body of the next card, whereby said cards are interlocked and spaced with their sheaths projecting one beyond another.
20. 7. In a card system, a series of cards, a sheath engaged with one margin of each card and comprising a transparent front strip and a back strip fastened together between their edges and extending respectively in front of and back of the card, said cards being assembled with the sheath of one card nested between the next card of the series and the front strip of the sheath therefor, whereby said cards are interlocked and spaced with their sheaths projecting one beyond another.
25. 8. In a card system, a series of cards, a sheath connected to each card adjacent to one margin thereof for protecting an index member for the card, said cards being longer than and projecting beyond the ends of the sheaths for engagement with a support for retaining the cards thereon, said cards being assembled with the sheath of each card nested between the sheath and the body of the next card in the series, whereby said cards are interlocked and spaced with their sheaths projecting one beyond another.
30. 9. In a card system, a series of sheaths arranged in nested relation with each other with each sheath projecting beyond the next sheath, said sheaths having transparent front walls adapted to cover index members and cards connected to said sheaths and extending one behind another.
35. 10. In a card system, a series of sheaths having transparent front walls adapted to cover index members and having parts adapting the sheaths to interlock with each other with each sheath projecting beyond the next sheath, and cards connected to said sheaths and extending one behind another.
40. 11. In a card system, the combination of a frame, a series of sheaths assembled in nested relation with each sheath projecting beyond the next sheath, said sheaths having transparent front walls adapted to cover index members, and cards connected to said sheaths and having retaining parts engaging the frame for retaining the cards and sheaths on the frame.
45. 12. In a card system, a series of cards each having a folded marginal portion, and a series of sheaths with transparent front walls containing said folded portions of the cards, means for retaining said cards in overlapping relation with each sheath overlapping and projecting beyond the next sheath.
50. 13. A unit for card systems, comprising a sheath having a pocket with a transparent front wall and a tongue back of said pocket and separated therefrom by a space adapted to receive a similar sheath for interlocking the sheaths, a card which is connected to said sheath and extends in between the pocket and the tongue of the sheath, and an index member for the card confined in the pocket of the sheath.
55. 14. A unit for card systems, comprising a sheath having a pocket with a transparent front wall and a tongue back of said pocket, a card which is connected to said sheath and extends in between the pocket and the tongue of the sheath, said card being longer than and projecting beyond the ends of the sheath, and an index member for the card confined in the pocket of the sheath.
60. 15. A unit for card systems, comprising a sheath having a pocket with a transparent front wall, a card connected at one margin to said sheath, an index member confined in the pocket of said sheath, and a separate card retained on said first mentioned card.
65. 16. A unit for card systems, comprising a sheath having a pocket with a transparent front wall, a card having a folded marginal portion confined in said sheath, and having means for retaining a separate card thereon, and an index member confined in the pocket of said sheath.
70. 17. In a card system, a series of units, each unit having a substantially rectangular card portion of relatively large area and adapted to bear reference matter, and a relatively narrow tongue in front of said card portion, each unit being arranged with one margin thereof nested between the tongue and card portion of the next unit and with each tongue only partially overlapping the next tongue, whereby said units are interlocked and said tongues provide exposed index portions in front of said card portions located one above another.
75. 18. In a card system, a series of units,

each unit having a substantially rectangular card portion of relatively large area and adapted to bear reference matter, and a relatively narrow tongue arranged at the front side of said card portion and adjacent to one edge thereof, each unit being arranged with one margin thereof nested between the tongue and card portion of the next unit and with each tongue only partially overlapping the next tongue, whereby said units are interlocked and said tongues provide exposed index portions in front of said card portions located one above another.

19. In a card system, a series of units having tongues at their front sides and arranged with one margin of each unit nested between the tongue and the body of the next unit and with each tongue only partially overlapping the next tongue, whereby said units are interlocked and said tongues provide exposed index portions in front of the units located one above another, the ends of said units projecting beyond the ends of said tongues for engagement with a frame for retaining the units thereon.

20. In a card system, a series of units, each unit having a substantially rectangular

card portion of relatively large area and adapted to bear reference matter and a relatively narrow tongue arranged at the front side of said card portion with its edges substantially parallel with opposite edges of said card portion, each unit being arranged with one margin thereof nested between the tongue and card portion of the next unit and with each tongue only partially overlapping the next tongue, whereby said units are interlocked and said tongues provide exposed index portions in front of said card portions located one above another.

21. A unit for card systems, comprising a card provided at its front side adjacent to one edge with a tongue which extends toward the opposite edge of the card and has a free edge portion substantially parallel with said edge of the card and providing an index portion for said card, said tongue terminating at its ends short of the ends of the card.

Witness my hand, this 15th day of May, 1917.
